Inventor
RANDOLPH J. MCLEAN JR. DEC'D.
BY RANDOLPH J. MCLEAN, ADM.

By William Clinton

Attorney

UNITED STATES PATENT OFFICE.

RANDOLPH J. MCLEAN, JR., DECEASED, LATE OF WOODSTOCK, NEW BRUNSWICK,
CANADA, BY RANDOLPH J. MCLEAN, ADMINISTRATOR, OF WOODSTOCK, CANADA.

RENEWABLE FUSE.

Application filed October 4, 1921. Serial No. 505,869.

To all whom it may concern:

Be it known that RANDOLPH J. MCLEAN, Jr., deceased, late a subject of the King of Great Britain, residing at Woodstock, Province of New Brunswick, Canada, did invent certain new and useful Improvements in Renewable Fuses; and I, RANDOLPH J. MCLEAN, administrator, a subject of the King of Great Britain, residing at Woodstock, 10 Province of New Brunswick, Canada, do hereby declare that the following is a full, clear, and exact description of the invention, such as will enable others skilled in the art to which it appertains to make and use the same.

The present invention relates to new and useful improvements in renewable fuses.

The primary object of the invention is the provision of a renewable fuse, so arranged that the fuse element can be readily removed, in case the same burns or breaks.

Another object of the invention is the provision of means whereby ready access may be had to the fuse element for replacement purposes if desired.

A further object of the invention is the provision of a renewable fuse such as above referred to, in which the caps are provided with suitable openings for permitting the escape of gas in case of the fuse element burning.

Another object of the invention is the provision of means for locking the caps and contact blades in the desired position against displacement.

A still further object of the invention is the provision of means for removably connecting the fuse element within grooves formed in the contact blades, and holding them in such position and preventing any undesired displacement thereof.

A still further object of the invention is the provision of a renewable fuse such as above referred to, which will be comparatively simple and inexpensive to manufacture, reliable and efficient in use, and readily operated.

With the above and other objects in view, the present invention resides in the novel features of construction, formations, combinations and arrangements of parts to be hereinafter more fully described, claimed and illustrated in the accompanying drawing, forming a part of the present application; and in which,

Figure 1 is a side view of a fuse constructed in accordance with the present invention;

Figure 2 is a vertical sectional view taken therethrough showing the fuse element in 60 position;

Figure 3 is a similar view with the fuse element removed;

Figure 4 is a plan view of the fuse element removed; 65

Figure 5 is an enlarged sectional view taken through the upper end of the fuse, at right angles to Figure 2;

Figure 6 is a plan view thereof; and,

Figure 7 is a detail view showing the locking mechanism.

Referring now to the accompanying drawing by corresponding characters of reference throughout the several views, the numeral 10 designates in general my improved renewable fuse, which comprises a casing 11 of cylindrical formation, formed from fibre or other non-conducting material, and terminally equipped with caps 12 and 13, formed in their ends with slots 14 having 80 inturned lips 15 to which the contact blades 16 and 17 are connected. 75

These caps 12 and 13 are likewise provided with suitable openings 18 partially closed by asbestos and wire fabric designated 85 at 19, to permit the gas contained within the casing 11 to escape therefrom in case the fuse element 20 burns out.

The inner ends of the contact blades are provided with grooves 21 in which the ends 90 of the fuse element 20 are placed. Latch members 22 are pivoted at 23 to the contact blades and are provided with finger grips 24 arranged so that the same can be moved readily to and from their operative positions. 95

In placing the fuse element 20 in position, the ends thereof are inserted in the grooves 21 and the latches 22 are moved to engage the same and cover up the said grooves to 100 prevent the displacement of the said element.

The cap 12 is retained in position by means of screws shown at 25 which engage notches 26 formed in the end of said cap. 105 The cap 13 is likewise retained in position by similar screws 27 and in addition by locking pins shown at 28.

These pins pass through sleeves 29 inserted in the side of the casing 11 and riv- 110

eted therein against displacement, and are adapted to engage openings 30 formed in the caps 13 so that when in the position shown in Figure 2 they will lock this cap 5 against any undesired displacement.

The inner ends of the pins 28 are formed with openings 31 which have inserted therein the free ends of the springs 32 which latter are engaged by the strips shown at 10 33, and these said springs are also bent around the inner ends of the sleeves 29, as clearly shown in Figure 7.

The strips 33 are provided with spring clips 34, which engage the free ends of the 15 springs 32 and retain the pins 28 in inoperative position, while additional clips shown at 35 are secured to the helical portions of the springs for supporting the latter against any undesired displacement.

20 When it is desired to replace the fuse element 20, the pins 28 are pushed inwardly by the springs 32 out of their engagement with the openings 30 until the clips 34 engage the free ends of the springs 32 thus retaining 25 the pins in their retracted position. The screw elements 27 are then loosened and the cap 13 may be readily removed carrying with it the contact blades 17. The lower latch is then removed from engagement with 30 the lower end of the fuse element 20 and the end thereof can be removed from the lower groove 21. A new fuse element is then inserted in the said lower groove and the lower latch moved to locking position. The upper 35 end of the fuse element is then placed in the upper groove 21 and at the same time the cap is replaced and the upper latch moved to locking position, the bevelled ends thereof forcing the pins 28 into the openings 30 locking the cap 13 in the desired 40 position.

From the foregoing description taken in connection with the accompanying drawing, it will be readily seen that a removable fuse 45 is provided which will fulfil all of the necessary requirements of such a device, and it should be understood in this connection that various minor changes in the specific details of construction can be resorted to 50 within the scope of the appended claims, without departing from the spirit or sacrificing any of the advantages of the invention.

Having thus fully described the invention, 55 what I claim as new and desire to secure by Letters Patent is:—

1. The herein described device including a casing, a cap engaging one end thereof, a contact blade carried by the cap, said blade 60 having a groove therein, a fuse element engaging said groove, and a latch pivoted to the contact blade for preventing the displacement of the said fuse element.

2. A renewable fuse of the character described, including a casing, a pair of caps 65

engaging the opposite ends thereof, contact blades carried by said caps and extending within the said casing, said contact blades having grooves therein, a fuse element engaged in said grooves, latches pivoted to the 70 contact members for closing the grooves and retaining the fuse element in position and means for locking one of the caps against displacement.

3. A renewable fuse of the type described, 75 comprising an insulating casing, caps engaging the opposite ends thereof, contact blades carried by the caps and extended into said casing, said contact blades having grooves formed therein, a fuse element engaged within said grooves, latches carried by the contact members and closing the 80 grooves and retaining the fuse element in position, and spring pins holding one of the said caps against displacement. 85

4. A renewable fuse of the type described comprising a fibre casing of cylindrical formation, caps engaging the ends thereof, said caps having slots in their ends and inturned lips at one edge of said slots, contact blades 90 secured to said lips and extending within the casing, said contact blades having grooves formed therein, a fuse element seated in said grooves, latches pivoted to the contact blades for closing said grooves and 95 retaining the fuse element against displacement, pins movable through the sides of the casing into engagement with one of the caps, and springs for actuating said pins. 95

5. A renewable fuse of the type described, 100 comprising a casing formed from insulating material, said casing being of cylindrical formation, caps engaging the ends of said casing, said caps having slots formed at the ends thereof, and lips at the edges of said slots extending into the casing, contact blades secured to said lips and projecting into the casing, said contact blades having grooves formed therein, a fuse element having its ends engaged within said grooves, 105 latch members pivoted to the contact blades for extension into the casing, and closing the grooves and retaining the fuse element against displacement from the grooves, sleeves inserted through the sides of the casing adjacent one end thereof, one of said caps having openings therein in alignment with the openings in the sleeves, pins 110 slideable through said sleeves for engagement with the openings in the cap, a spring engaging each of said pins, and means engaging the spring for retaining the pins in inoperative position, substantially as and for 115 the purposes set forth. 115

In witness whereof I have hereunto set 120 my hand.

RANDOLPH J. McLEAN,
Administrator of Randolph McLean, Jr., de-
ceased.
